Primary Examiner — T Chase Nelson*Assistant Examiner* — Sydney Margaret Parsley(74) *Attorney, Agent, or Firm* — Warren D. Schickli; Stites & Harbison PLLC(57) **CLAIM**

The ornamental design for a foot for hunting stand as shown and described.

DESCRIPTION

FIG. 1 is a perspective view of the foot for hunting stand; FIG. 2 is a top plan view thereof;

FIG. 3 is a bottom plan view thereof;

FIG. 4 is a left side elevational view thereof, the right side elevational view being a mirror image thereof;

FIG. 5 is a front elevational view thereof; and,

FIG. 6 is a rear elevational view thereof.

The broken lines illustrate portions of the foot for hunting stand that form no part of the claimed design.
